UNITED STATES PATENT OFFICE.

GEORGE S. HENSEL, OF PHILADELPHIA, PENNSYLVANIA, ASSIGNOR TO THE HENSEL, COLLADAY COMPANY, OF PENNSYLVANIA.

DESIGN FOR A SKIRT-PROTECTOR.

SPECIFICATION forming part of Design No. 31,164, dated July 4, 1899.

Application filed June 10, 1899. Serial No. 720,093. Term of patent 14 years.

To all whom it may concern:

Be it known that I, GEORGE S. HENSEL, a citizen of the United States, residing in the city and county of Philadelphia, State of Pennsylvania, have invented and produced a new and original Design for a Skirt-Protector, of which the following is a specification, reference being had to the accompanying drawings, forming part thereof.

5 The leading features of my design for a skirt-protector are a head, a brush pendent therefrom, and the representation of a serpentine rib on the face of said head.

Figure 1 represents a side elevation of a piece of skirt-protector embodying my design. Fig. 2 represents a section thereof on line $x-x$, Fig. 1.

In the drawings, A designates a piece of skirt-protector, the same being composed of the head B and the brush C, pendent therefrom. On the face of said head is the representation of a rib D, the same being of serpentine form.

Having thus described my invention, what I claim as new, and desire to secure by Letters 25 Patent, is—

The design for a skirt-protector substantially as shown and described.

GEORGE S. HENSEL.
